UNITED STATES PATENT OFFICE.

JOHN ELWOOD LAMBORN AND ROSS RICKARDS, OF DIXON, CALIFORNIA.

WASHING-MACHINE.

SPECIFICATION forming part of Letters Patent No. 448,526, dated March 17, 1891.

Application filed December 9, 1890. Serial No. 874,020. (Model.)

To all whom it may concern:

Be it known that we, JOHN ELWOOD LAMBORN and ROSS RICKARDS, of Dixon, in the county of Solano and State of California, 5 have invented certain new and useful Improvements in Washing-Machines; and we do hereby declare the following to be a full, clear, and exact description of the invention, such as will enable others skilled in the art 10 to which it pertains to make and use it, reference being had to the accompanying drawings, which form part of this specification.

Our invention relates to an improvement in washing-machines; and it consists in the 15 combination with the box or tub and the hinged roller-frame placed in its bottom, of a pivoted suspending-arm, the rub-board provided with a handle, springs for connecting it to the suspending-rod, and a spring for 20 catching over the end of the handle of the rub-board and holding the rub-board in a raised position, as will be more fully described hereinafter.

The object of our invention is to provide 25 a washing-machine in which the rub-board is suspended as shown, and which can be operated while the operator is in a standing position and thus bring no strain to bear upon his or her back.

30 Figure 1 is a side elevation, partly in section, the rub-board being shown in position upon the rollers ready for use, and its other positions when not in use being shown in dotted lines. Fig. 2 is a plan.

35 A represents the box or tub, which is supported by the legs B C, the legs C being made to project a suitable distance above the top of the tub, so as to form supports for the horizontal arms D, which extend any suitable distance outward. The upper ends of these legs 40 C are rigidly secured together by means of the cross-bar F, which forms a support for the rub-board when it is turned back, so as to be entirely out of the way. Pivoted between the 45 outer ends of the two arms D is the cross-shaft G, and rigidly secured to the center of this par-

tially-revolving rod or shaft G is the hanger H, which is provided with a head I upon its lower end. Pivoted upon this head I, by means of the flat springs J, is the rub-board L, which 50 is provided with the handle N. This handle enables the rub-board to be freely moved back and forth by the operator while standing in an erect position. As the rub-board is supported by the hanger H, all weight is 55 taken from the operator, who has simply to move it back and forth over the clothes to be washed and which are placed upon the rollers O, journaled in the frame P, which is hinged at one end to the bottom of the tub. This 60 frame is held in position by means of a catch or button Q, pivoted upon the bottom of the tub.

When the rub-board is not in immediate use, the outer end of its handle N is made 65 to catch under the spring R, which is fastened to the partially-revolving shaft G, journaled between the arms D, and by means of which the rub-board is suspended above the rollers, so as to leave the operator free to adjust the clothes upon the roller or perform any other operation necessary. When the tub is to be used for rinsing, the button Q is turned and the frame P is raised upon one end, so as to leave the body of the tub free 70 at the same time that the rub-board is turned back over the top of the cross-bar F, so as to be entirely out of the way. The springs J allow the rub-board to give sufficiently to prevent it from injuring the clothes and so as to 75 enable the operator to bring any desired amount of pressure to bear upon the clothes while operating.

From the above it will be seen that the parts are few and simple and that the finest 80 clothing can be washed without any danger of being torn or injured, as the operator can bring any amount of power desired upon them.

Having thus described our invention, we claim—

1. The combination of the box and the hinged frame, of rollers placed therein, with

the legs, the arms D, secured to the upper extended ends of the legs C, the shaft G, hanger H, rub-board L, springs J, handle N, spring-catch R, and the cross-bar F, substantially as shown.

2. The combination of the tub, the legs, the arms D, the shaft G, the rub-board suspended therefrom and provided with a handle N, and the spring-catch R, secured to the shaft, for catching over the upper end of the handle and

holding the rub-board in a raised position, substantially as described.

In testimony whereof we affix our signatures in presence of two witnesses.

JOHN ELWOOD LAMBORN.
ROSS RICKARDS.
